UNITED STATES PATENT OFFICE.

HARRY H. RUSSELL, OF PORTLAND, MAINE, ASSIGNOR TO THE E. T. BURROWES COMPANY, OF PORTLAND, MAINE, A CORPORATION OF MAINE.

CARD TABLE.

Application filed February 16, 1923. Serial No. 619,439.

This invention relates to improvements in light folding tables particularly adapted for card playing purposes.

The main object of the invention is to 5 simplify and cheapen the construction of tables of the type referred to while at the same time providing a strong durable structure of good appearance.

The invention, with other objects and advantages thereof, and the particular construction, combination, and arrangement of parts comprising the same will be understood from the hereinafter contained detailed description, when considered in connection with the accompanying drawings, 10 forming part hereof, and illustrating embodiments thereof.

In the drawings:

Figure 1 is a top plan view of a card table 20 constructed in accordance with the present invention.

Fig. 2 is a detail vertical section on an enlarged scale.

Fig. 3 is a detail top plan view, on an enlarged scale of a corner portion of the table.

Fig. 4 is an inverted top plan.

Fig. 5 is a detail view of a slightly modified form of top.

Fig. 6 is a vertical section of the modified 30 top structure of Figure 5.

Fig. 7 is a detail vertical section of a further modification.

The invention contemplates an improved construction in which the covering of cloth, 35 leatherette or the like commonly stretched over the pulp board top is entirely dispensed with and the main upper face portion of the top is left exposed and given an ornamental finish in imitation of leather or wood, 40 or colored in different shades. According to the teachings of the present invention the frame is provided with an interior top supporting portion extending below the upper face thereof, and a moulding part extending 45 inwardly over and above said top supporting portion, the top being arranged with its marginal portion engaged between the said top supporting portion and the moulding part.

Important novel characteristics of the invention also reside in the special construction and arrangement of parts providing a raised border portion or rail which tends 50 to prevent small articles from falling or rolling from the top, and whereby in withdraw-

ing cards from the table, the cards are caused to point or be tilted upwardly as they slide over the edge of the table, making it easy to grasp them with the thumb and fingers, and even the same into books.

While specific embodiments of the invention are illustrated in the drawings, it will of course be understood that minor changes and variations in the particular constructions shown, and the carrying out of the invention in other forms, as will appeal to those skilled in the art, and falling within the scope of the appended claims, may be practiced without departing from the spirit of the invention.

Referring in detail to the particular embodiment of the invention illustrated Figures 1 to 4 inclusive of the drawings, in this instance, the frame is shown as rectangular shape made up of bars 1 suitably secured 60 together. 2 designates the legs pivotally connected, as shown, to the frame to fold 65 within the same.

The frame is provided with an inner rabbeted or recessed portion 1^a having its bottom wall below the upper face 4 of the frame and forming a top supporting surface. The top 5 is provided with an upper rabbeted or reduced marginal portion 5^a, and 6 is a moulding extending inwardly from the upper part of the frame over said rabbeted portion 5^a of the top, said moulding serving to secure the top to the frame and concealing the marginal portion of the top from view, the moulding being preferably, as 70 shown, formed as a separate part and secured to the frame in any suitable way, for example, as illustrated, by brads or equivalent fastening members piercing the moulding and marginal portion of the top and 75 entering the frame.

The top 5 is preferably, as shown, of a thickness less than the height of the upper face 4 of the frame from the bottom wall of the recess and rests thereupon with its 80 upper face below the upper face 4 of the top, said moulding with the upper part of the frame constituting a raised rail or border that tends to prevent small articles from falling or rolling from the top. The moulding tapers inwardly, as shown, said moulding having an inwardly inclined or sloping 85 upper face portion 6^a extending below the plane of the main central upper face of the top, and a rounded bead like face portion 90

6^b at its outer edge adjoining the upper face of the frame and extending slightly above the same. This special construction functions to cause the cards to point or be tilted upwardly as they are slid over the upper edge of the table, making it easy to grasp the cards and even the same into books.

10 The top, which is preferably formed of pulp board is of a greater thickness or of a more substantial nature than the pulp board top members as commonly provided, to lend increased strength and stability to the structure, and the main upper face portion of the top inwardly of the moulding 15 6 is given an ornamental finish in imitation of leather or wood, or is colored in different shades.

19 In the construction illustrated Figures 1 to 4 of the drawings, the reduced marginal portion 5^a of the top 5 is formed by cutting or slicing the pulp board but it may be provided by other methods, moulding or shaping by pressure. In Figures 5 and 6 is illustrated 25 a construction of top in which the reduced marginal portion of the top is formed by compressing the edge of the board.

30 In Figure 7 of the drawings is illustrated a slightly modified construction in which the main upper face portion of the top instead of being disposed below the upper face of the frame extends flush with the upper face of the moulding and the upper face 35 of the frame. In this view 10 designates the frame and 11 the top seated on the bottom wall 12 of the recessed portion 13, and 14 is the moulding, the latter in this instance being rectangular shape and having 40 its upper face extending horizontally, flush with the upper face 10^a of the frame and the main upper face portion 11^a of the top 13, said moulding being of a thickness substantially equal to the height of the upper 45 face of the frame from the bottom wall 12 of the recessed portion 13. As in the preferred construction illustrated Figures 1 to 4, hereinbefore described, the main portion of the upper face 11^a of the top 11 is left 50 exposed and directly forms the table surface, the same being given a suitable ornamental finish.

55 By the particular construction and arrangement of parts hereinbefore described, the usual cloth covering for the top is entirely dispensed with; the main upper surface of the pulp board top member is left exposed, admitting of giving the same an

ornamental finish in imitation of leather or wood or the like to directly form the table 60 surface, and the full width of the frame rail is exposed without a break, the improved structure being of a simple inexpensive character while at the same time being strong and durable and of an attractive substantial 65 appearance.

70 The special moulding structure serves to secure the top to the frame and afford a neat finish, a raised border or rail being also provided which tends to prevent small articles from falling or rolling from the top of the table, and also functions to make the gathering of the cards from the table more easy.

75 What I claim is:

1. A card table comprising a frame having a recess extending around the inner marginal portion thereof, the bottom wall of the recess extending below the upper face of the frame, a top having an upper outer rabbeted portion seated on the bottom wall of the recess, and a moulding part extending inwardly from the upper part of the frame over said rabbeted portion of the top, said moulding part having an upper face portion sloping downwardly and inwardly below the plane of the upper face portion of the top.

2. A card table comprising a frame having a recess extending around the inner marginal portion thereof, the bottom wall of the recess extending below the upper face of the frame, a top having a marginal portion of less thickness than the distance of the upper face of the frame from the bottom wall of the recess, and seated on said bottom wall of the recess, and a separate inner moulding part seated in said recess over said marginal portion of the top and secured to the frame.

100 3. A light folding card table comprising an open frame having a recess extending around the inner marginal portion thereof, the bottom wall of the recess extending below the upper face of the frame, a top having an upper outer rabbeted portion of a thickness less than the distance from the upper face of the frame to the bottom wall of the recess seated on the bottom wall of the recess, and a separate inner moulding 105 part seated in said recess over said rabbeted portion of the top.

110 In testimony whereof I hereunto affix my signature.

HARRY H. RUSSELL.
